UNITED STATES PATENT OFFICE.

ELIJAH T. HARRIS, OF CHICAGO, ILLINOIS.

DESIGN FOR A GRATE-FRONT.

SPECIFICATION forming part of Design No. 20,821, dated June 9, 1891.

Application filed March 18, 1891. Serial No. 385,552. Term of patent 7 years.

To all whom it may concern:

Be it known that I, ELIJAH T. HARRIS, a citizen of the United States, residing at Chicago, in the county of Cook and State of Illinois, have invented and produced a certain new and useful Design for Fire-Place Grate-Fronts, of which the following is a full, clear, concise, and exact description, reference being had to the accompanying drawing, forming a part of this specification.

Grate-fronts consist of the upper portion, sometimes in the form of bars designed for preventing the fuel from falling out in front, and the ash-guard fitted thereto below and usually provided with a damper.

The accompanying drawing is a view of a grate-front, showing my design.

The leading feature of my design consists of a gorgon-face with open mouth in connection with scroll-work on each side thereof. Below this is shown open fret-work in the form of downwardly-extending ribs, these ribs being curved outwardly upon each side of the

center. Scroll-work in relief is shown at the extreme ends of the fret-work. Thus the head or face *a* is placed centrally, so as to appear between the scroll-work *b c*. The ribbed fret-work below is indicated at *d e*. The ribs *d e* are bent outwardly from the center *f*. Above these ribs between the straight plain *g* and the curved portion *h* appears the fluted ornamental edge *i*. At the outer ends of the ribbed fret-work appear the scrolls *k l* in relief. The scroll-work *b c* is extended downwardly to be on opposite sides of the fluted ornament *i*.

I claim—

The design for grate fronts, substantially as herein described and shown.

In witness whereof I hereunto subscribe my name this 5th day of March, A. D. 1891.

ELIJAH T. HARRIS.
